FIGURE 1.

Dec. 729

James H. Conklin of Peekskill N. Y.
assignor to.

Samuel B. Sexton of Baltimore Md.

Letters Patent No 729. - Dated Sept 11th 1855.

The schedule referred to in these Letters Patent and making part of the same.

To all whom it may concern:

Be it known that I, James H. Conklin of Peekskill
in the county of Westchester and State of New York have produced a new and original
book spine design.

and I do hereby declare that the follow-

ing is a full, clear and exact description of the same, reference being had to the annexed drawing
forming part of this specification in which

Fig. 1. is a view of front plate, and.

Figure 2. is a view of side plate.

The upper portion of the front plate A bears a raised rectangular tablet B, embellished at each end by the scroll figure a, and having in the middle portion the following inscription in raised capitals: "Washington Foundry Baltimore Md." The ends of plate A. are rounded and embellished with the arched figures b. Below the tablet B. are the doors c. each surrounded by the molding c. which is ornamented in bas relief by the chain of lozenges figures d. The middle portion of each door consists of a panel f. bearing in bas relief the curved cord g. enclosing the group of figures h. and i. The arrangement and configuration of the several ornaments on this plate are fully shown in figure 1.

The side plate F is embellished by the chain of circles l. and lozenges m. arranged as shown in the drawing, and extending around the bottom, top and rear portion of the plate, within the moulding D. The upper portion of the plate bears the inscription "S. B. Sector & Co" in raised capitals. Upon the plate are the raised panels G. H. I. J. all except J. surrounded by a moulding ornamented in bas relief by a chain of lozenge figures n. and all having a central panel embellished by bas-relief ornaments as follows. The panel G. bears the ornament R. composed of central figure c. p. and detached figures of radiating from the center of figure p. the whole enclosed by the cord m. The precise arrangement and configuration being as shown in the drawing. The panel H. bears the ornament T. enclosed by the cord U. The panel I. has an ornament V. similar to T. surrounded by the cord W. And the panel J. bears the figure X. enclosed by the cord Y. The precise configuration, and arrangement, of the several ornaments, being as delineated in figure 2.

I claim the design, configuration and arrangement of the ornaments in bas-relief on stove plates A & F. as herein described and shown in the drawing.

In testimony whereof, I have hereunto signed my name before two subscribing witnesses
